UNITED STATES PATENT OFFICE.

ALEXANDER C. MAURER, OF PHILADELPHIA, PENNSYLVANIA.

DESIGN FOR FRINGE.

SPECIFICATION forming part of Design No. 22,049, dated December 6, 1892.

Application filed November 3, 1892. Serial No. 450,911. Term of patent 7 years.

To all whom it may concern:

Be it known that I, ALEXANDER C. MAURER, a citizen of the United States, residing at the city of Philadelphia, State of Pennsylvania, have invented and produced a new and original Design for Fringes, of which the following is a specification, reference being had to the accompanying drawing, showing said fringe.

My design consists of a ribbed upper band A, having its upper edge scalloped, and a series of tassels C C, &c., depending from its lower edge, said tassels C being drawn together a short distance below the band A, as

shown at C' C', &c., and connected at said contracted parts by bands D D, &c., having scalloped edges E E both at top and bottom and a series of substantially-triangular openings F F, &c., being formed above bands D and between the tassels C.

What I claim is—

The design for fringes, substantially as herein shown and described.

ALEX. C. MAURER.
